Specification of Letters Patent.

Patented Mar. 9, 1915.

Application filed November 20, 1911. Serial No. 661,404.

To all whom it may concern:

Be it known that I, ROBERT E. L. JANNEY, a citizen of the United States, residing at Chicago, in the county of Cook and State of Illinois, have invented certain new and useful Improvements in Couplers, of which the following is a specification.

This invention relates to car couplers, and is primarily an improvement upon the invention disclosed in the copending joint application of Edmund P. Kinne and myself for couplers, filed January 21, 1911, and bearing Serial No. 603,858. Said joint invention provides, among other things, for preventing the reseating of the locking block on the lock-set ledge or shoulder while the knuckle is open to any material extent.

The present invention recognizes the fact that, due to wear, rust, intention or other causes the locking block may become reseated on the lock-set ledge or shoulder while the knuckle is in an open position, and, therefore, it is an important object of the present invention to provide for positively unseating the locking block from its lock-set position should the lock go back into lock-set position under any of the aforementioned conditions, and to cause it to move from the lock-set ledge onto the tail of the knuckle whereon it will ride and be maintained against going back into lock-set position during the closing of the knuckle.

It is furthermore designed to provide an improved anti-creep arrangement, whereby any movement on the part of the locking block, in its locked position, which may be caused by the action of the knuckle tail on the locking block, will be in a direction toward the anti-creep ledge or shoulder, rather than away from it, thereby to bring about a more intimate engagement of the locking block with the anti-creep rather than to tend to move the locking block out of engagement with the anti-creep ledge or shoulder; and to provide for positively moving the locking block out of engagement with the anti-creep ledge or shoulder in a very simple and efficient manner.

With these and other objects in view, the present invention consists in the combination and arrangement of parts, as will be hereinafter more fully described, shown in the accompanying drawings and particularly pointed out in the appended claims, it being understood that changes in the form,

proportion, size and minor details may be made, within the scope of the claims, without departing from the spirit or sacrificing any of the advantages of the invention.

In the drawings: Figure 1 is a vertical longitudinal sectional view, partly in elevation, of a coupler constructed in accordance with this invention and showing the parts in locked condition. Fig. 2 is a similar view showing the lock seated on the lock-set ledge and the knuckle free to swing open. Fig. 3 is a similar view showing the knuckle partly open, the lock having been unseated from the lockset and illustrating the impossibility of the lock being again seated on the lock-set ledge. Fig. 4 is an irregular horizontal sectional view taken on the line 4—4 of Fig. 1, the parts being in locked condition. Fig. 5 is a fragmentary plan view of the knuckle and the locking block; a portion of the coupler head being in section, showing the manner of guiding the locking block, and also showing in dotted lines, the relation of the knuckle tail and the locking block during the opening movement of the knuckle. Fig. 6 is a view similar to Fig. 5 showing the knuckle completely open and the position of the locking block with respect thereto. Fig. 7 is a detail sectional view on the line 7—7 of Fig. 4, the locking block being shown in dotted lines. Fig. 8 is a detail perspective view of the locking block. Fig. 9 is a view similar to Fig. 1, taken through the longitudinal center of the coupler head, the locking block being in elevation. Fig. 10 is a fragmentary cross-sectional view taken in front of the locking block.

Like reference characters designate corresponding parts in each of the several figures of the drawings.

Referring at first more particularly to Fig. 4 of the drawings, it will be seen that 20 designates a coupler shank having a head 21, a guard arm 22, lugs 23, a swinging knuckle 24 and a knuckle pivot pin 25. These parts are of any common or preferred construction and arrangement, and in themselves form no particular part of the present invention. Within the coupler head, there is provided the usual recess in which the tail of the knuckle moves, and which is adapted to receive the locking block, the knuckle opener, and the lock lifter. The floor 26 of this recess in the coupler head is provided near its mouth with a recess 27, in

which works a projection 28 (shown in Fig. 3) depending from the bottom of the knuckle tail. This recess is open at its rear end so as to permit the projection to move into and 5 out of the recess, while its outer or forward end is closed so as to form an abutment or stop against which the projection 28 is designed to strike and thus limit the opening of the knuckle.

10 It will here be explained that, due to wear on the projection 28 and the closed end of the recess 27, the knuckle may open to a greater extent than originally intended, and, therefore, it is an important object of the 15 present invention to take care of such condition and insure the proper operation of the locking block under such a condition.

The locking block of this invention is a somewhat irregular although substantially 20 rectangular block of metal, and is designed to lie between and engage the knuckle tail and the guard arm wall of the recess in the coupler head in the locked position of the knuckle, as clearly shown in Fig. 4 of the 25 drawings. In the top of the locking block there is a recess 44, extending in a direction longitudinally of the coupler head, and bridged by a loop 45, to which is connected the lifter 46. This lifter is provided with a 30 longitudinal slot 47, whereby the lifter may drop to a certain extent, accommodated by the recess 44 in the top of the block. The top of the block has another recess 48, which opens through the front of the block and 35 also through what will be termed the knuckle side of the block, for the purposes of accommodating a portion of the knuckle opener, as will be hereinafter explained. At the front of the block and at the knuckle side 40 thereof there is a depending toe or projection 49, through the medium of which the block is pulled from its lock-set position and is prevented from returning to the lock-set position by coöperation with the knuckle 45 tail as will be hereinafter described. On the guard arm side of the locking block and at the rear of the block there is a vertically extending shoulder 50, and across the rear face of the block just below the top thereof 50 there is a transverse horizontally disposed ledge or shoulder 51. The upright shoulder or abutment 50 works in a vertical groove 31 in the guard arm wall of the recess in the coupler head, and engages back of the front 55 wall of said groove so as to limit the forward movement of the locking block. The transverse ledge or shoulder 51 is designed to underlie a horizontally disposed ledge or shoulder 30 extending transversely across 60 the rear wall of the recess in the head of the coupler, so as to provide the anti-creep feature of this invention, as will hereinafter appear. The under side of the ledge or shoulder 30 is an anti-creep abutment, while 65 the top or upper face of said shoulder is the

lock-set seat, on which the locking block is designed to rest when the block is not employed for locking the knuckle.

With the locking block in its locked position, as shown in Fig. 4 of the drawings the 70 lower portion of the upright shoulder 50 of the locking block is in engagement with the front wall of the groove 31, as shown in Fig. 7, and therefore the locking block cannot move forwardly under the influence of 75 the action of the knuckle tail on the block. However the locking block is free to move rearwardly, to a limited extent at least, so far as any rear obstruction is concerned, and, therefore, the locking block may move 80 rearwardly under the influence of the action of the knuckle tail on the block. When in 85 its locking position, the part 51 of the locking block underlies the anti-creep shoulder 30, and is thereby held against upward displacement. However, the block is free to move rearwardly, to a limited extent at least, so far as any rear obstruction is concerned. This fact is utilized by locating the anti-creep shoulder 30 transversely across 90 the back of the recess in the coupler head and to the rear of the locking block, whereby the tendency of the locking block is to work further under the anti-creep ledge or shoulder, under the action of the knuckle 95 tail, rather than to work forwardly and away from the anti-creep ledge or shoulder. This is a very important feature of the present invention, in that it effectually prevents the locking block from working from beneath and disengaging the anti-creep ledge or shoulder in a very positive and simple manner.

The locking block may be elevated from its locking position, so as to release the 105 swinging knuckle, by being pulled from above by the lifter 46, such lifter being loosely connected to the block at a point in rear of its center of gravity, whereby, on being elevated by the lifter, the front portion of the locking block will tilt downwardly, thereby swinging the part 51 of the block forwardly and out from beneath the anti-creep ledge or shoulder 30, thus automatically and positively freeing the lock 110 from the anti-creep ledge or shoulder merely by the action of lifting the locking block. Of course, the locking block could be lifted by pushing upwardly upon the bottom thereof, the only essential being that the point 115 of application of force to the block for lifting the same be in rear of its center of gravity, as will be readily understood. This tilting of the locking block, to permit it to disengage from the anti-creep ledge or 120 shoulder, is not interfered with by the upright shoulder 50 on the locking block, because the latter has sufficient play in the groove 31 to permit of such tilting of the 125 block. See Fig. 7 of the drawings.

During the elevation of the locking block, its rear face will wipe upwardly across the front of the ledge or shoulder 30, until the bottom of the locking block has passed 5 slightly above the horizontal plane of the top of the ledge or shoulder 30, whereupon the block will tilt to a greater extent and the rear portion of the bottom of the block will swing over the top of the shoulder 30 10 and will seat thereon when the block is lowered. When thus seated upon the lock-set seat, the locking block will thereafter remain in an elevated position above the knuckle tail so as to permit of the knuckle 15 being swung to an open position.

With the locking block on the lock-set seat, and the coupler in lock-set position, it is proposed, on opening the knuckle, to draw the locking block forwardly from its lock-set seat onto the tail of the knuckle, in substantially the same way as is shown and described in my joint copending application hereinbefore referred to. This feature is 20 accomplished by means of a transverse shoulder extending across the top of the knuckle tail, coöperating with the toe or projection 49 on the bottom of the locking block. This shoulder is preferably provided 25 by forming a groove 36 across the top of the knuckle tail and opening through opposite sides thereof and in which the toe or projection 49 is designed to work. The portion 36^c of the knuckle tail between the groove 36 and the rear end of the tail supports 30 the locking block when it has been pulled forwardly from its lock-set position and constitutes a shoulder extending across the knuckle tail. The front wall or face of this shoulder 36^c is inclined rearwardly of 35 the knuckle in opposite directions from an intermediate point, as shown at 36^b and 36^c, and the top of the shoulder is chamfered as at 36^d to form a continuation of the face or wall portion 36^c. The effect of 40 this formation of the front wall of the shoulder 36^a is to widen the groove at both ends, for the purpose as will hereinafter appear. It is not desired to immediately pull the locking block from its lock-set 45 position on the initial opening of the movement of the knuckle, and therefore the front face of the shoulder 36^a on the knuckle tail is inclined at 36^b, so that the toe or projection 49 of the locking block will not contact with 50 the front face or wall of said shoulder until the knuckle has swung open to some material extent, (see Fig. 5), and when it does come into contact with said face or wall, the further opening of the knuckle will of 55 course positively pull the locking block forwardly until it becomes supported upon the shoulder 36^a of the knuckle tail. So long as the locking block remains upon the knuckle tail with its toe or projection 49 60 in the groove 36 or in front of the front

wall of the shoulder 36^a, the locking block will be prevented from working rearwardly into its lock-set position. With the locking block resting on the knuckle tail, if the knuckle is moved to its closed position, the 70 knuckle tail will wipe beneath the locking block, and when it passes beyond the locking block, into the full-line position shown in Figs. 4 and 5, the locking block will be unsupported and will drop down into its 75 locking position. Thereafter the knuckle may be released by lifting the locking block and seating it upon the lock-set seat.

Under normal conditions, the knuckle being open, as shown in Fig. 6, the toe 49 of the locking block will lie in front of the shoulder 36^a, and hence the locking block will be prevented from going back on the lock-set shoulder. However, due to wear or other causes, as hereinbefore suggested, 80 the knuckle may open to a greater extent than is shown in Fig. 6, and it is to take care of this condition that the shoulder 36^a is chamfered as at 36^d, in order that should the lock, when lowered, seat on the lock-set shoulder, the toe 49 will lie in front of the chamfered portion. Under these conditions, when the knuckle moves to its closed position, the wall of the chamfered portion 36^d will operate as a cam to pull the locking block forwardly and this action will be continued by the wall portion 36^c of the knuckle tail, whereby the locking block will be unseated from the lock-set ledge and pulled on to the top of the shoulder 36^a on 85 the knuckle tail, where it will ride until the knuckle tail escapes from beneath the locking block and the latter will drop to its locking position.

It will now be understood that under normal or ordinary conditions, the chamfered portion 36^d does not come into use, and is useful only when wear takes place or other conditions arise wherein the knuckle opens to an abnormal extent and the locking block becomes seated upon the lock-set shoulder. It is preferred to chamfer the knuckle tail, rather than to cut it off entirely in order to have the benefit of as much metal as possible in the hooked terminal of the shoulder 36^a, 105 which hooked terminal is designed to embrace and pull against the end portion 43 of the knuckle-throwing lever 39 which is pivoted upon trunnions 40 and 41 fitting in bearing sockets 33 and 34 in the coupler 110 head. When the locking block is lifted to release the knuckle, the top of the block strikes the upper free end portion 42 of the knuckle throwing lever 39 and rocks it on its trunnions so as to swing the lower end 115 portion 43 transversely of the coupler head and thereby kick the knuckle open.

Having thus described my invention, what I claim is:

1. A car coupler comprising a coupler 120

- head, a swinging knuckle having a transverse shoulder on the tail thereof, a lock, and a lock-set shoulder on the head in rear of the front face of the lock, said lock having a seat portion to seat upon the lock-set shoulder and also provided at the front of the lock with a depending portion to engage the front wall of the shoulder on the knuckle tail and thereby hold the lock 10 with its seat portion in front of the lock-set shoulder when the lock is dropped from an elevation above the lock-set position and in an open position of the knuckle, a portion of the front face of the shoulder on the knuckle tail which is beyond the position of the projection on the lock in the normal open position of the knuckle being shaped to permit said projection to lie in front of said portion of the shoulder in an 20 abnormal open position of the knuckle, said portion of the shoulder being eccentric to the pivot of the knuckle and operating to pull the lock forwardly from the lock-set seat by the closing of the knuckle.
- 25 2. A car coupler comprising a coupler head, a swinging knuckle having a transverse shoulder on the tail thereof, a lock, and a lock-set shoulder on the head in rear of the front face of the lock, said lock having a seat portion to seat upon the lock-set shoulder and also provided at the front of the lock with a depending portion to engage the front wall of the shoulder on the knuckle tail and thereby hold the lock 30 with its seat portion in front of the lock-set shoulder when the lock is dropped from an elevation above the lock-set position and in an open position of the knuckle, the extremity of the transverse shoulder on the 35 extension knuckle-tail being chamfered to receive the depending portion of the lock in an abnormal open position of the knuckle, said chamfered portion being eccentric to the pivot of the knuckle and operating to 40 pull the lock forwardly from the lock-set seat by the closing of the knuckle.
- 45 3. A coupler comprising a coupler head, a swinging knuckle provided with a transverse shoulder on the tail thereof, said shoulder having a face on its forward side eccentric with respect to the pivot of the knuckle, a lock having a projection, and lock-setting means including a lock-set shoulder disposed wholly to the rear of the front face 50 of the lock, the projection on the lock engaging the front face of the shoulder on the knuckle tail when the knuckle is open, and the eccentricity of the eccentric face of the shoulder on the knuckle tail being such as to draw the lock forwardly during the closing of the knuckle.
- 60 4. A coupler comprising a coupler head, a swinging knuckle provided with a transverse shoulder on its tail, said shoulder having its front face inclined rearwardly of the 65 knuckle in opposite directions from an intermediate portion, a lock having a projection, and a lock-set seat disposed wholly to the rear of the front face of the lock, the projection on the lock being in position to 70 be engaged by one of the inclined faces of the shoulder during opening of the knuckle and when the lock is on the lock-set seat, whereby to positively draw the lock forwardly from its lock-set position during 75 opening of the knuckle, and said projection engaging the other inclined face of the shoulder during the initial closing movement of the knuckle to prevent re-setting of the lock on the lock-set seat during the 80 closing of the knuckle.
5. A coupler comprising a coupler head, a swinging knuckle provided upon its tail with a shoulder extending transversely thereof, a lock having a projection, and a 85 lock-set seat disposed wholly to the rear of the front face of the lock, the projection on the lock engaging the forward face of the shoulder during opening of the knuckle to positively draw the lock forwardly from its 90 lock-set position, the initial point of contact of the projection with the front face of the shoulder being disposed inwardly from the inner side of the tail of the knuckle to permit of an initial opening movement of the 95 knuckle before engagement with the projection.
6. A car coupler including a coupler head having a cavity therein, a lock in the cavity, a lock-set seat on the rear wall of the cavity, 100 an anti-creep shoulder on the rear wall of the cavity, and lock-lifting means for moving the lock out from beneath the anti-creep shoulder, lifting it into an elevated position above the lock-set seat and permitting it to seat upon said lock-set seat.
7. A car coupler including a coupler head having a cavity, a lock in the cavity, a combined lock-set seat and anti-creep shoulder on the rear wall of the cavity, and lock-lifting means for moving the lock out from beneath the anti-creep shoulder, lifting it to an elevated position and permitting it to seat upon the lock-set seat. 110
8. A coupler knuckle having a coupling hook and a tail portion, said tail portion having on its upper surface a transverse shoulder extending beyond the outer side of the knuckle, the front edge portion of the shoulder on the extension thereof being 115 chamfered.
9. A coupler knuckle having a coupling hook and a tail portion, said tail portion having on its upper surface a transverse shoulder, the front face of said shoulder being inclined rearwardly in opposite directions from an intermediate portion. 125
10. A coupler knuckle having a coupling hook and a tail portion, said tail portion having on its upper surface a transverse 130

shoulder, the front upper edge portion of said shoulder at the outer side of the knuckle being chamfered.

11. A car coupler including a coupler head, a lock therein, a lock-set seat at the rear of the lock, an anti-creep shoulder at the rear of the lock, the upper rear portion of the lock being adapted to underlie the anti-creep shoulder in locking position of the lock, the rear bottom portion of the lock being adapted to seat on the lock-set seat

10

in the lock-set position of the coupler, and lock lifting means for moving the lock forwardly and out from beneath the anti-creep shoulder, lifting it to an elevated position and permitting it to move rearwardly and seat upon the lock-set seat.
